HYDRAULICALLY ACTUATED DIAPHRAGM PUMP

Paul J. Eifel, Chicago, Ill., assignor to Hills-McCanna Company, Chicago, Ill., a corporation of Illinois
Filed Apr. 6, 1960, Ser. No. 20,462
2 Claims. (Cl. 103—44)

The present invention relates to diaphragm pumps in which the pumping diaphragms are actuated hydraulically in a manner such that the pressure on the diaphragms of the fluid being pumped is opposed by the pressure of hydraulic actuating fluid on the diaphragms. Diaphragm pumps, particularly hydraulically actuated pumps, can be used to great advantage in pumping fluids which must not be allowed to escape to the external environment even in small quantities.

A diaphragm pump is inherently susceptible of being completely sealed against the escape of the fluid being pumped as long as the diaphragm remains unbroken and impervious to the fluid. However, purely mechanical actuation of a pump diaphragm tends to create stresses in the diaphragm which can cause it to fail prematurely in service, particularly when pumping fluid under high pressure. Stresses on a pumping diaphragm caused by the pressure of the fluid being pumped can be greatly minimized by actuating the diaphragm hydraulically in a manner such that the hydrostatic pressure of the hydraulic actuating fluid opposes the pressure force on the diaphragm of the fluid being pumped.

However, the actuation of a pump diaphragm by hydraulic fluid presents a number of challenging problems, which are the particular concern of the present invention.

One object of the invention is to provide a hydraulically actuated diaphragm pump having a new and improved construction and mode of operation which assures maintenance of maximum operating efficiency and output capacity of the pump at all times, while at the same time avoiding the application of excessive hydrostatic pressure to the pumping diaphragm.

Another object is to provide a hydraulically actuated diaphragm pump of improved construction which functions automatically as an incident to energization of the pump to fill hydraulic actuating space within the pump with an optimum quantity of diaphragm actuating fluid and to completely free the hydraulic actuating space of entrapped air.

Another object is to provide an improved, hydraulically actuated diaphragm pump which is so constructed that an optimum volume of actuating liquid is maintained in hydraulic actuating space in the pump, even though liquid may be lost from this space through leakage or otherwise, by operation of an air-liquid discriminating valve of simple, trouble free construction which serves to release and replace with an optimum quantity of liquid any air or other gas which for any reason may have been entrapped in the hydraulic actuating space.

A further object is to provide an improved diaphragm pump as recited in the preceding objects in which new and improved pump structure provides for efficient operation of the air-liquid discriminating valve, while at the same time obviating any necessity for interconnecting this valve with other working parts of the pump.

Another object is to provide a hydraulically actuated diaphragm pump having a new and improved construction which provides for efficient high speed operation of the pump, while at the same time serving to admit supplementary quantities of hydraulic fluid into the hydraulic actuating space within the pump only as necessary to maintain an optimum quantity of fluid in the actuating space and in a manner which substantially avoids any

2

reduction in the pressure within the actuating space below ambient pressure conditions.

An additional object is to provide an improved diaphragm pump as recited in the previous objects in which reductions in the pressure within the hydraulic actuating space below atmospheric pressure conditions are avoided and optimum supplementary quantities of hydraulic fluid are added to the hydraulic actuating space by the operation of a simple reliable valve which operates independently of mechanical connections to other working parts of the pump.

A further object is to provide an improved hydraulically actuated pump as recited in the foregoing objects in which the diaphragm is supported and protected against excessive hydrostatic actuating pressure in a manner which obviates subjecting the diaphragm to damaging stresses.

Other objects and advantages will become apparent from the following description of the exemplary form of the invention illustrated in the drawings, in which:

FIGURE 1 is a perspective view of a pump embodying the invention;

FIG. 2 is a fragmentary, horizontal sectional view of the pump taken along the plane indicated by the line 2—2 in FIG. 1;

FIG. 3 is a fragmentary sectional view on a greatly enlarged scale showing the air-liquid discriminating valve incorporated in the pump and appearing in FIG. 2;

FIG. 4 is a fragmentary sectional view of the structure appearing in the central portion of FIG. 3, but showing the valve in closed rather than open position;

FIG. 5 is a horizontal sectional view taken along the line 5—5 of FIG. 3;

FIG. 6 is a fragmentary sectional view on a greatly enlarged scale taken along the line 6—6 of FIG. 3;

FIG. 7 is an exploded perspective view of the air-liquid discriminating valve used in the pump; and

FIG. 8 is a fragmentary sectional view showing the pump diaphragm upon completion of a discharge stroke.

The diaphragm pump 10 forming the exemplary embodiment of the invention illustrated comprises a pump body 12, mounted as shown in FIG. 1, on one end of a frame 14 that houses a power driving mechanism 16 of generally conventional construction, which reciprocates a pump actuating plunger 18. The plunger 18 extends through a sealing sleeve 20 into a horizontal bore 22 in the housing 12. The bore 22 is made somewhat larger in diameter than the plunger 18, thus avoiding frictional engagement of the plunger with the bore. A high pressure seal 24 supported within the sleeve 20 in encircling relation to the plunger 18 is designed to prevent fluid from escaping from the bore 22 around the plunger.

Reciprocation of the plunger 18 is used to effect hydraulic actuation of a pumping diaphragm 26, as will presently appear.

The diaphragm has a circular shape and is formed of a tough, flexible material. The circumferential marginal edge of the diaphragm is tightly clamped between two sections 28, 30, of the housing 12, which are connected together by screw elements 32, FIGS. 1 and 2. The two housing sections 28 and 30 are formed by metal castings which clamp the diaphragm with sufficient force to preclude the escape of fluid around the clamped periphery of the diaphragm.

Thus supported, the diaphragm 26 extends across a circular cavity 34 formed by two complementary circular recesses 36, 38 defined in the opposed housing sections 28 and 30 in facing relation to each other, as shown in FIG. 2. The cavity 34 thus formed is partitioned by the diaphragm 26 to define a pumping chamber 40 and a hydraulic actuating chamber 42 which are alternately con-

70

tracted and expanded by actuation of the diaphragm, as will presently appear.

The pumping chamber 40 is connected through a bore 44 with inlet and outlet check valves 46, 48. As shown, two inlet valves 46 are used in tandem to connect the bore 44 with an intake line 50, and two outlet check valves 48 are used to connect the bore 44 with a discharge line 52.

Movement of the diaphragm 26 to expand and contract the pumping chamber 40 produces a pumping action which forces fluid from the intake line 50 into the discharge line 52.

As previously intimated, diaphragm pumps of this character have special advantages in pumping corrosive chemicals and other fluids which can not be allowed to escape even in small quantities. The space within the pump, including the pump chamber 40, is completely sealed against the escape of fluid as long as the diaphragm 26 remains intact. The importance of avoiding rupture or failure of the diaphragm 26 places a premium on eliminating failure producing stresses on the diaphragm, particularly in the pumping of fluids under high pressure.

The diaphragm 26 is actuated by the cyclic application of hydraulic pressure to the diaphragm in opposition to the pressure on the diaphragm of the fluid being pumped. Thus, the diaphragm is actuated by a quantity of hydraulic fluid contained within an enclosed pump actuating space which includes the actuating chamber 42 and a plenum space 54, FIG. 2, which receives the inner end of the reciprocable plunger 18. The plenum space 54 is formed in part by a space within the previously mentioned bore 22. The bore 22 is concentric with the diaphragm 26 and merges with a counterbore 56 which extends from the bottom of the cavity 38 toward the plunger 18 through a major portion of the body section 30. The counterbore 56 provides space for receiving the plunger 18, when the latter is fully advanced, together with additional space for accommodating diaphragm biasing structure to be described.

The plenum space 54 communicates freely with the actuating chamber 42. Advancement of the plunger 18 forces fluid from the plenum space 54 into the actuating chamber 42, creating hydrostatic pressure on the diaphragm 26 which forces the diaphragm to the left with respect to FIG. 2, to expel fluid from the pumping chamber 40.

Retraction of the plunger 18 removes the plunger from a volume of the plenum space 54 equal to the displacement of the plunger. This would, of itself, create a reduced pressure condition within the pumping space which would cause movement of the diaphragm 26 in an intake direction to effect a corresponding expansion of the pumping chamber 40, provided the actuating space is completely filled with an optimum volume of hydraulic fluid which does not change during operation of the pump.

However, severe problems can arise during operation of the pump, due to difficulties involved in maintaining an optimum quantity of hydraulic fluid in the hydraulic actuating space, which is designated generally in FIG. 2 by the number 58. In the first place, it is impossible as a practical matter to prevent leakage of hydraulic fluid from the actuating space 58 past the movable plunger 18. Such leakage of actuating fluid can produce an out of phase relationship of the diaphragm movement to the plunger movement.

When an optimum volume of hydraulic fluid is present in the actuating space 58, advancement of the plunger 18 to its innermost position displaces the diaphragm 26 to its extreme discharge position. In the event the volume of hydraulic fluid in the actuating space 58 has been diminished by leakage, the diaphragm 26 does not move fully through its normal excursion in its discharge direction upon movement of the plunger 18 to its innermost position. The result is a diminution in the active dis-

placement of the diaphragm 26 with a corresponding loss of pumping capacity.

As a practical matter, it is necessary to provide some means for supplying make-up fluid to the actuating space 58 to compensate for fluid lost from this space. Because of the cyclic lowering of pressure in the actuating space 58, there is often a tendency for an excess volume of fluid to fill up in the actuating space 58 through any means used to add make-up fluid to this space.

The effect of excess fluid in the space 58 is to reduce the intake excursion of the diaphragm 26, with a consequent diminution in pumping efficiency, and to apply excessive stress to the diaphragm when the plunger 18 moves to its innermost position.

Thus, in order to obtain maximum pumping efficiency, it is necessary that the diaphragm 26 move in phase with the reciprocating motion of the plunger 18 through the normal excursion of the diaphragm between normal limits of the diaphragm motion. It will be appreciated from the above that this ideal phase relationship of the diaphragm motion to the plunger motion can be disturbed by either an increase or a decrease in the volume of fluid in the space 58. Moreover, the problem of compensating for losses of fluid from the space 58, while at the same time avoiding a build up of excess fluid in this space, becomes more complicated as the cyclic speed of the plunger 18 is increased. This stems from the fact that increases in the operating speed of the pump have previously been accompanied by increases in the degree to which the pressure in the hydraulic actuating space has been reduced on an intake stroke. This is particularly true when pressure reductions in the hydraulic actuating space have been relied on to effect movement of the pumping diaphragm in an intake direction. To increase the speed of the diaphragm, it has been necessary to increase the pressure reduction in the hydraulic actuating space, as intimated.

Losses in pumping efficiency and other difficulties can arise due to the presence of entrapped air in the hydraulic actuating space within a pump of this character. The compressibility of the air has the effect of reducing the excursion of the diaphragm.

Such difficulties associated with the construction and operation of prior diaphragm pumps of this character are eliminated in the improved pump 10 provided by this invention. Moreover, maximum operating efficiency of the improved pump, even at very high operating speeds, is assured by the operation of extremely simple and inherently reliable pump structure which functions as an incident to energization of the pump to provide and maintain an optimum volume of hydraulic actuating fluid in the actuating space 58, while at the same time making special provision for obviating any lag in the motion of the diaphragm 26 relative to the reciprocating motion of the plunger 18. As will be described in further detail, the maintenance of an optimum volume of liquid in the space 58 is achieved through a functional cooperation of diaphragm biasing and stop means with an extremely simple air-liquid discriminating check valve to release entrapped air from the space 58 and supply an optimum quantity of liquid to the space as an incident to energization of the pump.

Thus, as illustrated in FIG. 2 provision is made for maintaining a positive pressure within the actuating space 58 during an intake stroke of the pump until the diaphragm 26 has been retracted to its extreme intake position. The diaphragm 26 is moved in its intake direction not by the force of differential fluid pressure on the diaphragm but by the action of a biasing spring 60 continuously applied to the central portion of the diaphragm.

Preferably, the central portion of the diaphragm 26 is clamped between two pressure disks 62, 64, which are attached by a screw fastener 66 to an adjacent end of a hollow spring support sleeve 68 which extends from the disk 64 into the counterbore 56, as shown in FIG. 2.

The biasing spring 60 is a coiled compression spring. It is disposed in encircling relation to the sleeve 63 between a radial flange 70 on the plunger end of the sleeve and an annular spring seat 72 anchored in the counterbore 56 against axial movement by an expandable snap ring 74 seated in the wall of the counterbore 56.

Movement of the diaphragm 26 in its intake direction is positively terminated, when the diaphragm reaches its extreme intake position, by abutting engagement of the sleeve flange 70 with the bottom of the counterbore 56.

The force of the spring 60 on the diaphragm 26 operates to maintain a positive pressure on fluid within the actuating space 58 until the sleeve 63 bottoms in the counterbore 56 as recited. Normally, the intake movement of the diaphragm 26 will be positively terminated in this manner simultaneously with movement of the plunger 18 to its fully retracted position. In the event there is a deficiency of liquid in the space 58, the sleeve 63 will bottom in the counterbore 56 before the plunger reaches its fully retracted position. Continued movement of the plunger in an intake direction then causes an immediate reduction in pressure within the space 58, to allow entry of additional liquid into the space through a special air-liquid discriminating check valve 80 communicating with the upper extremities of the space 58 through passages which provide for free rise up to the valve of any air entrapped in the actuating space.

Preferably, the valve 80 is mounted, as shown, in the housing section 30 at the bottom of a reservoir 32 for hydraulic actuating fluid formed in the upper portion of the housing 12. The valve 80 is covered with hydraulic fluid and opens automatically in response to a drop in the pressure within the space 58 below ambient pressure conditions to admit liquid into the space 58.

After stopping in its fully retracted position, the plunger 18 accelerates from a standing start in an advancing direction which tends to force fluid from the space 58 out through the valve 80. During the period when the plunger 18 is near the retracted end of its stroke, any air in the space 58 rises into underlying relation to the valve 80 through either a vertical internal bore 84 communicating with the counterbore 56 or a generally horizontal bore 86 communicating with the upper extremity of the actuating chamber 42.

By virtue of its capacity to discriminate between air and liquid, the valve 80 will remain open during initial advancement of the plunger 18, to allow air to escape from the space 58 while responding to an incipient discharge of liquid through the valve to immediately close and preclude loss of actuating liquid from the space 58.

It should be appreciated, in this connection, that the release of air from the space 58 during advancement of the plunger 18 serves to create reduced pressure conditions in the space 58 during the subsequent retraction of the plunger 18, with the result that the displaced air is replaced with liquid from the reservoir 32.

The construction of the air-liquid discriminating valve 80, which enables it to discriminate between air and liquid in allowing the escape of air while precluding the escape of liquid, is illustrated in FIGS. 3 to 7.

As shown in FIG. 3, the valve 80 comprises a small valve cavity 88 of generally cylindrical shape located centrally within a valve housing 90. Preferably, the valve housing 90 is formed by a cylindrical plug element 92 threaded into a downwardly open central bore 94 in a bushing element 96, which is removably threaded into the upper end of the housing bore 84. A cylindrical well 93 in the upper end of the plug element 92 coacts with the flat bottom 100 of the bushing bore 94 to define the valve cavity 88.

This cavity encases and provides limited clearance around a short, generally cylindrical valve closure element 102.

The valve closure element 102 is dimensioned diametrically to provide limited radial clearance 104 be-

tween the periphery of the valve element and the cylindrical wall of the cavity 88. This provides a restricted flow passage extending axially past the valve element 102 to connect the bottom of the cavity 88 with the top of the cavity. A small axial bore 106 is formed in the plug element 92 in concentric relation to the cavity 88 to connect the actuating space 58 with the bottom of the cavity 88 below the valve element 102. The reservoir 32 communicates with the valve cavity 88 through an outer bore 108 formed in the valve housing element 96 in coaxial relation to the inner bore 106 and opening into the top of the cavity 88.

An upwardly extending stem, tang or pintle 110 centrally formed on the upper side of the valve element 102 projects a substantial distance upwardly into the outer bore 108. The stem or tang 110 is flattened on three longitudinal sides, as shown in FIG. 6, to have a triangular shape in transverse section and to provide three restricted fluid flow passages 112 extending through the bore 108 alongside the stem.

The valve element 102 has an axial length somewhat shorter than the axial length of the cavity 88, thus providing for limited axial movement of the element 102 between an upper, valve closed position, shown in FIG. 4, and a lower, valve open position, shown in FIG. 3. The flat bottom surface 100 of the bore 96 forms a valve seat encircling the bore 108, which is engaged by an O-ring seal 114, carried on the upper side of the valve element 102, to close the valve 80 against the escape of fluid from the space 58 upon movement of the valve element 102 against the force of gravity to its upper position.

A transverse kerf or slot 116 cut into the lower face of the valve element 102 extends across the adjacent end of the inner valve bore 106 to connect the bore 106 with the restricted cylindrical passage 104 around the valve element 102 when the latter is in its lower, open valve position, shown in FIG. 3.

Upon lowering of the pressure within the actuating space 58 below ambient pressure conditions, due to a deficiency of fluid within the space 58, a differential pressure force is applied to the valve element 102 which is supplemented by the force of gravity on the valve element to cause it to move downwardly to its open position. A quantity of liquid flows through the passages 112 alongside the stem 110, through the flow passage 104 around the valve element and through the slot 116 and inner bore 106 into the space 58.

In the event air is entrapped in the space 58, the air rises through the bore 106 and upon advancement of the plunger 18 from a standing start flows around the valve element 102 and out through the restricted passages 112.

The movable valve element 102 is rather light in weight and will respond to a rather small upward force to rise to its closed position.

However, the valve element 102 will remain in its open position to allow a substantial quantity of air to escape during initial advancement of the plunger 18. Because of its compressibility, and because of its very low viscosity and its inherently low fluid friction upon motion, air can flow at a substantial rate through the restricted passages around the valve element 102 without forcing the valve element into its closed position. Thus, the valve 80 permits a substantial quantity of air to escape from the space 58 during each successive advancing stroke of the plunger 18 until the space is completely purged of air.

At the same time, the valve 80 is sensitive to an incipient outflow of liquid through the valve to effect an immediate closure of the valve, which prevents loss of liquid from the space 58. In contrast to the physical characteristics of air, liquid is not only virtually incompressible, but it has a very high viscosity and a very high fluid friction upon flowing as compared to air. Hence, an incipient outflow of liquid out through the inner bore 106

brings this relatively viscous fluid into engagement with the under side of the valve element 120. This impingement of the liquid on the valve element, together with the frictional drag on the valve element of liquid beginning to flow through the restricted passage 104 around the valve element and through the restricted passages 112 alongside the stem 110 snaps the valve element 102 into its closed position.

While the air-liquid discriminating valve 80 operates to admit only an optimum volume of liquid into the space 58, provision is made for releasing any excess liquid which may for any reason have become entrapped in the space 58.

An excess of liquid in the space 58 will cause the diaphragm support disk 62 to bottom against the floor of the housing recess 36. The disk 62 substantially covers the bore 44 and serves, in conjunction with the curved peripheral edge 120 of the recess 36, to provide strong support to the diaphragm, see FIG. 8. During continued advancing movement of the plunger 18, excess liquid is released from the space 58 by opening of a pressure release valve 122 connected between the counterbore 56 and the reservoir 82, as shown in FIG. 2.

In general, the pressure relief valve 122 comprises a compression spring 124 housed within a sleeve 126 to urge a pointed plug 128 against a seat 130. Fluid escaping past the plug 128 is discharged into the reservoir 82 through a port 132 in the sleeve 126.

The level of hydraulic liquid in the reservoir 82 can be observed in a transparent filler stem 134 connected with the reservoir 82 below the normal level of liquid in the reservoir.

It will be appreciated that the invention is not necessarily limited to the illustrated embodiment, but includes variants and alternatives within the spirit and scope of the invention expressed in the claims.

The invention is claimed as follows:

1. A hydraulically actuated diaphragm pump comprising, in combination, housing means defining a pressure cavity, a diaphragm extending across said cavity to form a flexible partition separating the cavity into a pumping chamber and a hydraulic actuating chamber, a pump intake spring connected to act on said diaphragm to urge the latter in a direction to expand said pumping chamber and contract said actuating chamber, positive stop means coacting with said diaphragm to positively limit motion thereof in pump chamber contracting and expanding directions, means defining an enclosed plenum space communicating with said actuating chamber and forming therewith a pump actuating space, a reciprocable displacement element movable within said plenum space to effect alternatae contraction and expansion thereof, a pressure relief valve communicating with said pump actuating space to relieve excess pressure therein, a gas-liquid discriminating check valve including means defining a valve cavity located above said actuating space, means defining an inner valve passage having an inner end opening into the uppermost portion of said hydraulic actuating space and having an outer end opening into the bottom of said valve cavity, said inner valve passage being positioned so that the elevation of every portion thereof is at least equal to that of said inner end thereof, means defining an outer valve passage opening into the top of said valve cavity, a liquid reservoir extending above said check valve and being connected to said outer valve passage for continuously supplying liquid thereto; said check valve including a check valve disc movably disposed in said valve cavity and biased by gravity to move between an upper, valve closed position in which the valve disc closes said outer passage against the outflow of fluid therethrough and a lower, valve open position; said disc being slotted on the underside thereof and being dimensioned in relation to said cavity to provide

when the disc is in the lower position thereof passage space around the valve disc for the inflow of fluid from said outer passage into said hydraulic actuating space, a valve actuating tang on said valve disc extending into one of said passages for both the upper and lower positions of the valve disc, and said tang being dimensioned in transverse section to provide limited passageway space extending through said one passage past said tang for allowing either the inflow of liquid through said check valve into said actuating space or the escape of gas from said actuating space through said check valve when said disc is in its lower position and to respond to an incipient outflow of liquid from said actuating space through said check valve to move said valve disc to said upper position thereof.

2. A hydraulically actuated diaphragm pump comprising, in combination, housing means defining a pressure cavity, a pumping diaphragm extending across said cavity to form a flexible partition separating the cavity into a pumping chamber and a hydraulic actuating chamber, means defining an enclosed plenum space communicating with said actuating chamber and forming therewith a pump actuating space, a displacement element coacting with said plenum space to effect alternate contraction and expansion thereof, a gas-liquid discriminating check valve including means defining a valve cavity located above said actuating space, means defining an inner valve passage having an inner end opening into the uppermost portion of said hydraulic actuating space and having an outer end opening into said valve cavity, said inner valve passage being positioned so that the elevation of every portion of the inner valve passage is at least equal to that of said inner end of the inner valve passage, means defining an outer valve passage opening into said valve cavity, a liquid reservoir extending above said check valve and being connected to said outer valve passage for continuously supplying liquid to said outer valve passage, said check valve including a check valve element movably disposed in said valve cavity and biased to move from a valve closed position in which the valve element closes said outer passage against the outflow of fluid therethrough to an open position; said check valve element and said valve cavity defining means being shaped and dimensioned in relation to each other to define, when the check valve element is in the open position thereof, an intermediate passage space connecting said outer valve passage with said inner valve passage to provide for the inflow of fluid from said outer passage into said hydraulic actuating space; a valve actuating tang on said valve element extending into one of said inner and outer valve passages for both the open and closed positions of the valve elements, and said tang being dimensioned in transverse section to provide limited passageway space extending through said one valve passage past said tang when said valve element is in the open position thereof to provide for both the intake of liquid into said hydraulic actuating space through said valve and the escape of gas from said hydraulic actuating space through said valve when the latter is open and to respond to an incipient outflow of liquid from said hydraulic actuating space through said valve to move said valve element to the closed position thereof.
